Primary Examiner — Zenia Bennett(74) *Attorney, Agent, or Firm* — Salter & Michaelson(57) **CLAIM**

The ornamental design for a jewelry snap, as shown and described.

DESCRIPTION

FIG. 1 is a perspective view on a pocket of a jewelry snap;
 FIG. 2 is a perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof;
 FIG. 9 is an exploded perspective front view thereof; and,
 FIG. 10 is an exploded perspective rear view thereof.
 The broken lines shown in the drawing views are included for
 the purpose of showing environmental structure that forms no
 part of the claimed design.
